UNITED STATES PATENT OFFICE.

LOUIS W. HOTTEL, OF CHICAGO, ILLINOIS.

DESIGN FOR A PNEUMATIC TIRE.

Application filed February 12, 1923. Serial No. 5,150. Term of patent 14 years.

To all whom it may concern:

Be it known that I, LOUIS W. HOTTEL, a citizen of the United States, residing at Chicago, in the county of Cook and State of Illinois, have invented a new, original, and ornamental Design for a Pneumatic Tire, of which the following is the specification, reference being had to the accompanying drawing, forming part thereof.

Figure 1 is a face view and Figure 2 a side view of the pneumatic tire showing my new design.

I claim:

The ornamental design for a pneumatic tire as shown.

In witness whereof, I have hereunto subscribed my name.

LOUIS W. HOTTEL
